CRICKET CANE

John E. Unger, Chicago, Ill.

Application October 8, 1951, Serial No. 250,249

4 Claims. (Cl. 46—175)

2

My invention relates to toys designed to make noise, and more particularly to the clacking variety of toy generally called a cricket, and one object is to incorporate such a toy in a cane for facility in handling the toy and applying the same for the emission of the clacking sound.

A further object is to design a cane which may be short for striking over a table or elevated surface, or long for striking on the ground, the cricket toy being incorporated in the body of the cane.

Another object is to construct the improved cane with means for actuating the cricket toy on the depression of the cane when applying the same to a table or floor.

An additional object is to construct the improved toy with few and simple parts.

With the above objects in view, and any others which may suggest themselves from the description to follow, a better understanding of the invention may be had by reference to the accompanying drawing, in which—

Fig. 1 is an elevation, partly in section, showing one form of the cane and the position of the cricket toy in relation to the same;

Fig. 2 is a top plan view of the showing in Fig. 1, with the cricket toy shown in full;

Fig. 3 is a section on the line 3—3 of Fig. 1;

Fig. 4 is a section, partly in elevation, of a modified form of the cane; and

Figs. 5 and 6 are, respectively, sections on the lines 5—5 and 6—6 of Fig. 4.

In accordance with the foregoing, specific reference to the drawing indicates a conventional form of cane at 10, the same being a wooden rod about a foot long for the table type of cane or about three feet long for the floor type. In either case, the upper end of the rod carries a knob 11 as a handle; and for one form of the invention the lower portion of the rod 10 enters slidably into a base 13. The latter is of cylindrical form and somewhat pointed at the lower end, as indicated at 14; and the wall of the base is vertically slotted on opposite sides, as indicated at 16, to receive the end portions of a cross-pin 17 carried by the lower portion of the rod 10. The rod is thus locked in the base 13, but has leeway for a limited longitudinal movement relative to the same by virtue of the travel of the pin 17 in the slots 16.

The rod 10 carries a conventional cricket toy 20 at a point above the base 13; and the reel 21 of the cricket toy is inclined to meet the top of the base 13 and concaved in its free end as shown at 22 to clear the rod 10.

The position of the cricket toy 20 relative to the base 13 is such that the reed 21 is in the normal or idle position when the pin 17 of the rod 10 is in the upper end of the base slots 16. Now, in case the rod 10 is depressed, the reed 21 acts to produce the clacking noise; and the tension of the reed 21 serves to raise the rod 10 after the pressure thereon is released.

For economy of manufacture, it is expedient to interpose the cricket toy 20 between upper and lower sections of the rod 10. As shown in Fig. 4, the rod sections have a common longitudinal bore 25 which registers with a perforation 26 in the cricket toy. A dowel 27 is driven to pass through the perforation 26 and lodge in the sections of the bore, thereby uniting the rod sections with the cricket toy. It is preferable that the dowel 27 be an iron screw on which the rod sections are threaded as they are assembled to receive the cricket toy between them, this construction making for ample rigidity and providing a metallic reinforcement for the wooden rod.

The modified form of the invention shown in Figs. 4 to 6 employs the basic construction 25 of the form first described, but eliminates the pin 17 and slots 16. Instead, the lower portion of the rod 10 is reduced inside the base 13 to form a plunger 30 having a head 31 at the bottom; and a compression spring 32 is interposed between the head 31 and the lower end of the base cavity. The depression of the rod 10 compresses the spring 32; and the latter acts to return the rod to its original height when pressure on the same has been released, a cross-pin 35 driven from the wall of the base 13 over the head 31 of the plunger serving as a stop in this connection.

While the action of the modified toy is the same as the one originally described, its purpose 40 is to insure the return or rise of the rod 10 in case the reed 21 of the cricket toy 20 is not sufficiently responsive in this respect. Thus, the spring 32 insures the return of the rod to its original or raised position; and the extent to 45 which the spring may be compressed also insures the engagement of the reed 21 with the top of the base at all times.

It will now be evident that the novel toy, whether in the original or modified form, provides a carrier for the cricket toy which dispenses with manual pressure on the same in order to operate it. Canes are a handy facility as toys, and have had wide popularity when used for shooting caps. In the present instance, the facility of the cane is retained without the fire

or injury hazard, and the cane is so constructed as to operate the popular cricket toy by the common or well-known mode of application of the cane, that is, to a table, floor or pavement. Also, the spring feature of the cricket toy reed is utilized in both forms of the invention to procure the return stroke of the cane, the modified form adding a special booster in the form of the spring 32 to insure this function. Further, it is necessary to make only one perforation in the cricket toy to adapt the same to the cane carrier; and this adaptation is fortified by inserting the cricket toy between sections of the cane rod which are reinforced by a metallic core both to keep them together and clamp the cricket toy rigidly between them. Finally, it will be apparent that the cane is made of only two major parts which may be fabricated by well-known machine methods, so that the toy may be produced in quantities at low cost.

While I have described the invention and its modification along specific lines, various minor changes or refinements may be made therein without departing from the principle thereof, and I reserve the right to employ all such changes and refinements as may come within the scope and spirit of the appended claims.

I claim:

1. A noise-making toy comprising a rod formed with a handle at one end, a base at the other end, said rod being movable relative to the base, and a clacking device carried by the rod and including an actuator directed toward said base, the movement of the rod in the direction of the base inducing the operation of said actuator, said clacking device being interposed between sections of the rod.

2. A noise-making toy comprising a rod formed with a handle at one end, a base at the other end, said rod being movable relative to the base, and a clacking device carried by the rod and including an actuator directed toward said base, the movement of the rod in the direction of the base inducing the operation of said actuator, said rod being made up of two longitudinally divided sections, and said clacking device being interposed between the latter.

3. A noise-making toy comprising a rod formed with a handle at one end, a base at the other end, said rod being movable relative to the base, and a clacking device carried by the rod and including an actuator directed toward said base, the movement of the rod in the direction of the base inducing the operation of said actuator, said clacking device having a sheet metal shank formed with a perforation, said rod being made up of two longitudinally divided sections formed with communicating longitudinal bores in registration with said perforation when said shank is inserted between said sections, and a dowel lodged in said bores and passing through the perforation to secure the assembly of the sections and said shank.

4. A noise-making toy comprising a rod formed with a handle at one end, a base at the other end, said rod being movable relative to the base, and a clacking device carried by the rod and including an actuator directed toward said base, the movement of the rod in the direction of the base inducing the operation of said actuator, said clacking device having a sheet metal shank formed with a perforation, said rod being made up of two longitudinally divided sections formed with communicating longitudinal tapped bores in registration with said perforation when said shank is inserted between said sections, and a screw threaded in said bores and passing through the perforation to secure the assembly of the sections and said shank.
